UNITED STATES PATENT OFFICE.

CHARLES H. HATCH, OF FREDONIA, NEW YORK, ASSIGNOR TO MERRITT MANUFACTURING COMPANY, OF LOCKPORT, NEW YORK, A CORPORATION OF NEW YORK.

VENEER-CUTTING MACHINERY.

1,248,490.

Specification of Letters Patent.

Patented Dec. 4, 1917.

Application filed March 26, 1917. Serial No. 157,475.

To all whom it may concern:

Be it known that I, CHARLES H. HATCH, a citizen of the United States of America, and resident of Fredonia, county of Chautauqua, and State of New York, have invented certain new and useful Improvements in and Relating to Veneer-Cutting Machinery, of which the following is a specification.

10 This invention relates to certain improvements in veneer cutting machinery; and the objects and nature of my invention will be readily understood by those skilled in the art in the light of the following explanation of the accompanying drawing illustrating what I now believe to be the preferred mechanical expression or embodiment of my invention from among other forms, arrangements and constructions within 20 in the spirit and scope thereof.

In veneer cutting machinery, it is necessary for proper production, that the relative lateral positioning of the knife and pressure blade be varied as the direct spacing of said parts is varied to change the thickness of the veneer produced. For instance, where the spacing between the knife and blade is increased or decreased horizontally to increase or decrease the thickness of the veneer, it is necessary that the relative lateral positioning of the knife and blade be also correspondingly varied vertically according to an approximately fixed ratio, and usually in machines of the general type illustrated hereby, this is about two to one, *i. e.* the vertical or lateral spacing should be equal to about one half the horizontal (or so-called radial) spacing.

Heretofore, the horizontal or radial spacing has been controlled to vary the thickness of the veneer produced, by shifting the pressure blade approximately radially of and toward and from the work (the log) and the cutting edge of the knife, through 45 the medium of a hand wheel controlling an adjusting worm and sector or by other setting means, while the required lateral or vertical setting of the blade with respect to the knife which was then necessary in view 50 of the changed horizontal spacing of the knife and blade, was effected through the medium of two vertical stop screws which had to be separately adjusted by hand to raise or lower the blade to the desired horizontal 55 plane with respect to the horizontal

plane occupied by the cutting edge of the knife. The manipulation of these two stop screws is a time consuming operation requiring more or less skill. Also, this separate adjustment requires experience and skill on the part of the operator to know at what elevation the blade should be set for each horizontal adjustment of the blade, and although essential this is an adjustment that operators are liable to overlook 60 or neglect as each new setting of the blade for a different veneer requires separate adjustment to attain the proper vertical positioning of the blade.

It is an object of my invention to cause 70 the blade to automatically assume the proper position with respect to the knife at each operation of setting the blade for a different veneer, and to set and position the parts for a different veneer production by 75 a single manual operation.

It is a further object of the invention to automatically bring about the proper relative positioning of the blade and knife at the same time that the manual setting operation takes place, and to thereby avoid the separate operations of manually adjusting stop screws, and of manually setting the parts whenever it is desired to produce a different veneer.

A further object of the invention is to provide means whereby but one manual operation will be required to bring about proper relative positioning and spacing of the blade and knife with respect to each 80 other and the log whenever parts are shifted for the production of a different veneer.

The invention consists in certain novel features of construction and in combinations and arrangements as more fully and particularly set forth hereinafter, and apparatus embodying my invention is characterized in whole or in part by means necessitating the accurate relative lateral positioning of the knife and blade with respect to 95 the spacing of the knife and blade whenever the parts are set to produce a different veneer so that each setting operation automatically causes the knife and blade to assume the predetermined relative lateral positioning required by any particular spacing of said parts to produce a certain veneer.

In the accompanying drawings:—

Figures 1 and 2, are cross sections, some- 110

what diagrammatically illustrating portions of a veneer cutting machine embodying my invention, said views showing the parts in different adjustments.

- 5 Fig. 3, is a section taken longitudinally of the pressure blade and knife bars and somewhat diagrammatically illustrating certain parts of a veneer cutting machine embodying my invention.
- 10 In the veneer cutting machine illustrated for purposes of explanation, the pressure blade 1, is mounted in and normally fixed to the front edge portion 2 of a cap or pressure bar and is arranged to bear against the 15 surface of the log (or other work) which is held in and rotated by suitable chucks as will be readily understood by those skilled in the art. When set for veneer cutting, the pressure blade bears against the log in rear 20 of the vertical plane occupied by the cutting edge 3 of the upwardly extending veneer cutting knife and also above the horizontal plane occupied by said knife edge.

The pressure bar is here shown as a casting, approximately triangular in cross section having rearwardly extending top leg or plate 4, rearwardly extending bottom leg or plate 5, and vertical end walls or plate 6.

The end walls are formed with alined 30 bearing openings or sleeves 7 arranged a distance in rear of the front edge portion of the bar, and these sleeves receive corresponding eccentric portions 8 of a hollow shaft or tube 9 by which the rear portion of the bar 35 is supported and on which it is vertically rockable to permit its front edge portion 2 carrying the pressure blade, to rise and fall.

The hollow shaft 9 is rotatably mounted on a shaft 10 which is supported by end 40 blocks or boxes 11 slidable in guide ways in the frame ends 12, as will be readily understood by those skilled in the art. The concentric end portions of the hollow shaft 9 are mounted in hangers 13.

45 The veneer cutting knife extends upwardly and forwardly from the front upper portion of the knife bar or carriage 14 which is here shown in the form of a casting triangular in cross section and embodying vertical end walls 15, and a downwardly and rearwardly inclined top plate or leg.

The knife bar is pivotally hung from the lower ends of hangers 13 through the medium of alined pivot pins 16 arranged at the 55 rear portions of the end walls 15 of the knife bar. As those skilled in the art understand, suitable means are provided to control the position of the knife bar to set and maintain the pitch of the knife, but my invention 60 is not concerned with such means.

In the embodiment illustrated, the pressure bar is arranged above and parallel with the knife bar, and the front portion 2 of the pressure bar is arranged between with 65 its ends spaced from the front portions of

the vertical end walls 15 of the knife bar, and with the pressure blade and cutting edge of the knife approximately meeting in their most advanced relative positions.

In the example illustrated, the pressure 70 blade 1 is moved horizontally toward or from the log to decrease or increase the horizontal spacing between the blade and knife and consequently to correspondingly vary the thickness of the veneer produced, by rotating the hollow shaft 9 to throw the eccentrics 8 forwardly, or by rotating said shaft in the opposite direction to throw said eccentrics rearwardly, and thereby bodily move or slide the pressure bar horizontally 75 by the cam or eccentrics 8 in the sleeve 7 of said pressure bar.

The pressure bar is rockable vertically on and its rear portion, is upheld by the hollow shaft, and suitable means are provided to 80 uphold the front portion of said bar and to cause the same to rise and fall (as the bar is moved horizontally rearwardly and forwardly) with a predetermined proportionate length of vertical movement with respect to the length of the horizontal movement.

In the particular example illustrated, the front portion of the pressure bar is upheld by vertical screws 18, one at each end 85 thereof, passing through tapped holes in lugs 19 projecting from the ends of the bar. These screws depend from the lugs and the lower ends thereof abut and rest on the upwardly and rearwardly inclined smooth top 100 surface 20 of blocks 21 upheld by abutments or rear enlargements 22 rigid with and rising from the top surface of the knife bar and located at the end portions thereof usually beyond the ends of the pressure 105 blade and below the projecting end lugs 19 of the pressure bar, so that the abutments 22, the inclined surfaces 20, and the screws 18 are arranged at opposite edges of the path followed by the veneer as it passes from 110 the knife and moves down and rearwardly over the top surface of the knife bar. In other words, the sheet of veneer passes rearwardly between the opposite end enlargements 22 and blocks 21, although I do not 115 wish to so limit my invention.

The front portion of the pressure bar is upheld and supported by the projecting lower end of the screw 18 resting on the top surface 20 of a suitable support or abutment, 120 and hence this projecting screw end forms a pressure-bar-upholding support, foot or rest 23 which is preferably rounded or of semi spherical formation, approximately as shown, at its surface that contacts the inclined plane 20.

The inclined plane 20 is elongated in the general direction of horizontal movement of the pressure bar, and the foot 23 slides thereon and longitudinally thereof as the 130

pressure bar is moved horizontally by its setting mechanism and the weight of the pressure bar holds the foot down on said plane. The plane 20 controls the elevation 5 or vertical position of the pressure blade 1, and said plane is so arranged and inclined that when the pressure bar is approximately at its limit of forward movement toward the log the pressure blade will approximately 10 contact the cutting edge of the knife and will be approximately at its limit of downward movement with respect to said cutting edge, and when the pressure blade is approximately at its limit of rearward 15 movement from the knife edge said blade will be held thereby at its extreme elevation so long as the foot 23 maintains its pressure bar supporting engagement with the top surface of the support or abutment 21.

20 The top surface of the support 21 is preferably smooth to permit the rounded foot 23 to freely slide thereon in riding up and down plane 20 as the pressure bar is moved horizontally and to facilitate the cam or 25 wedging action of the inclined plane in elevating the pressure bar as its foot 23 moves up the plane during the rearward movement of the bar, and in permitting said bar to drop as its foot 23 travels down the plane 30 during the forward movement of the bar.

When the eccentric shaft 9 is rotated, by any suitable means, to advance the pressure bar horizontally toward the knife edge 3 the foot 23 slides forwardly on the plane 20 and 35 hence the pressure blade is automatically depressed as it advances. When the shaft 9 is rotated in the opposite direction the pressure bar is withdrawn from or moved rearwardly from the log and knife and the foot 40 slides rearwardly on plane 20 and consequently automatically elevates the pressure blade as said blade is withdrawn.

As hereinbefore explained, it is desirable that the vertical or lateral position of the 45 blade should always bear an approximately certain relation to the horizontal, set or spaced position of the blade with respect to the knife edge. For instance in the embodiment illustrated, it is desirable that the 50 vertical movement of the blade should be equal approximately to one half the horizontal movement of the blade, and hence in this instance, the angle of inclination of the plane 20 is such as to require the blade 1 to 55 move vertically approximately one half the distance said blade moves horizontally whenever the pressure bar is shifted toward or from the log or the knife edge, by the rotation of the eccentric shaft or by any other 60 means that might be employed to set or control the position of the pressure blade with respect to the knife edge.

Any suitable mechanism can be provided 65 for manually (or otherwise) setting the pressure bar to change the thickness of the

veneer produced, and merely as an example of means that can be employed for this purpose, I show the eccentric shaft 9 and sleeves 7 hereinbefore described, and an upright hand lever 25 fixed to said shaft and located 70 between a pair of sleeves or collars 26, 27, loosely mounted on corresponding eccentric portions 28 of said shaft, and each formed with a worm sector 29 meshing with worms 30 carried by shafts 31 mounted in the top 75 plate 4 of the pressure bar and provided with hand wheels 32.

One of the loose sleeves 26 is provided with a side locking notch 33 arranged in advance of a corresponding side locking notch 80 34 with which the other sleeve 27 is provided, and the hand lever 25 is swingable laterally on an intermediate transverse pivot and is provided with opposite locking projections 35, one of which is adapted to enter 85 one of said notches while the other is adapted to enter the other locking notch. The lever can thus be swung to lock either worm sector to rotation with the eccentric shaft while releasing the other sector from the 90 shaft.

A suitable hand controlled latch 37 is usually provided to operatively lock the lever to and permit its release from either of the worm sector sleeves, or to permit the 95 lever to assume an intermediate position operatively disconnected from both sleeves, and when in this intermediate position the lever can be utilized to rotate the eccentric shaft to quickly advance or withdraw the pressure 100 bar, or to swing the same upwardly to clear the knife, as will be readily understood by those skilled in the art, the pressure bar setting mechanism described being old.

When either worm sector is locked to the 105 eccentric shaft through the medium of the hand lever, the worm meshing with that sector can be actuated by its hand wheel to horizontally shift the pressure blade with a slow and measured movement to accurately 110 determine the thickness of veneer to be cut. If it is desired to quickly change the thickness of veneer while the machine is in operation, the hand lever can be released from one sector sleeve, and then swung either forwardly or rearwardly to change the width of opening between the blade and knife from an initial working adjustment to a 115 second working adjustment, and consequently the thickness of veneer, and then 120 can be swung laterally to throw its locking projection into the locking notch of the other sector sleeve, said notch being in advance of or behind the notch of the other sleeve.

During all of these various quick or measured horizontal adjustments of the pressure blade, the required relative lateral positioning of the blade and knife will be automatically and constantly maintained, so that the 130

single manual operation will automatically result in the proper relative vertical positioning of the blade and knife required by the particular horizontal adjustment of said 5 manual operation.

I do not wish to limit my invention to any particular pressure bar, knife bar, pressure blade, and knife formations, and I herein employ the terms pressure blade and knife 10 in a broad sense to include any formations performing the functions of the blade and knife illustrated.

I do not wish to limit the broad features 15 of my invention to means wherein the manual setting mechanism is applied directly to the pressure bar to move the same horizontally nor wherein the relative adjustment for horizontal spacing is necessarily applied to the pressure bar, as I wish to 20 broadly cover means wherein the proper relative positions of the blade and knife are automatically maintained when a relative adjustment between said parts takes place for production of a different veneer, nor do 25 I wish to limit the broad features of my invention to the inclined plane and foot device for automatically maintaining proper positioning of the blade and knife.

It is evident that various changes, modifications and variations might be resorted to 30 without departing from the spirit and scope of my invention and hence I do not wish to limit myself to the exact disclosures hereof but consider myself entitled to all such 35 departures as fall within the spirit and scope of the invention.

What I claim is:—

1. In a veneer cutting machine, a veneer cutting knife, a coöperating pressure blade, 40 and mechanism for changing the relative spacing of said parts for varying the thickness of veneer produced and for automatically and simultaneously varying the relative lateral positioning of said parts.

45 2. In a veneer cutting machine, a veneer cutting knife, a coöperating pressure blade, manually controlled setting mechanism for changing the spacing of the knife and blade for the production of different veneer, and 50 means for automatically shifting the relative lateral positioning of said parts whenever the spacing is varied.

3. In a veneer cutting machine, a veneer cutting knife, a coöperating pressure blade, 55 mechanism for changing the relative set of said knife and blade to vary the thickness of the veneer produced, and means for automatically changing the relative lateral positioning of said parts by the act of varying 60 the set thereof and in proportion to the variation in the set.

4. In a veneer cutting machine, a veneer cutting knife, a coöperating pressure blade, and manually actuated means for simultaneously varying the relative set and the 65

relative lateral positioning of the blade and knife by a single operation, for changing the thickness of veneer produced.

5. In a veneer cutting machine, a veneer cutting knife, a coöperating pressure blade, 70 and mechanism automatically maintaining the relative lateral positioning of the knife and blade according to the set thereof and varying in proportion to the variation of the set, and embodying means whereby the 75 relative set of the knife and blade can be varied for changing the thickness of veneer produced.

6. In a veneer cutting machine, a veneer cutting knife, a coöperating pressure blade, 80 and manually controlled mechanism for determining the relative set and lateral positioning of the knife and blade to change the thickness of veneer produced, said mechanism involving means automatically shifting 85 the relative lateral positioning of the blade and knife at a predetermined ratio with respect to changes in the relative set of said parts.

7. In a veneer cutting machine, a veneer cutting knife, a coöperating pressure blade, means for shifting the relative positioning and setting of the blade and knife for changing the thickness of veneer produced and for automatically causing the predetermined 95 lateral positioning between the blade and knife required by any particular relative setting of said parts to produce a certain veneer thickness.

8. In a veneer cutting machine, a veneer cutting knife, a coöperating pressure blade, 100 means whereby the relative spacing and lateral positions of said parts can be shifted to vary the thickness of veneer produced, and means automatically shifting and maintaining 105 the lateral positioning of said parts at a predetermined fixed ratio with respect to the spacing of said parts.

9. In a veneer cutting machine, a veneer cutting knife, a coöperative pressure blade 110 movable toward and from the knife and also movable laterally with respect to the knife, manually actuated means for shifting said blade, and means for automatically controlling the lateral position of the blade as the 115 blade is moved toward and from the knife.

10. In a veneer cutting machine, a veneer cutting knife, a coöperating pressure blade movable toward and from the knife to vary the relative spacing between the knife and blade, and means for automatically moving the blade laterally with respect to the knife as the blade is moved toward and from the knife, said means maintaining a fixed predetermined ratio between the lateral movement of the blade and the movement of the blade toward and from the knife. 120

11. In a veneer cutting machine, a veneer cutting knife, a coöperating pressure blade, mechanism for changing the relative set of 130

said knife and blade to vary the thickness of the veneer produced, and means for automatically changing the relative lateral positioning of said parts by the act of varying 5 the set thereof and in proportion to the variation in the set, said means embodying a longitudinally inclined surface and a foot engaging the same.

12. In a veneer cutting machine, a veneer 10 cutting knife, a pressure bar providing a pressure blade coöperating with the knife, said pressure bar provided with a foot, an abutment provided with a longitudinally inclined surface on which said foot rests and 15 along which it is longitudinally movable as the bar is moved to carry the blade toward and from the knife, and means for moving the bar toward and from the knife, said blade being automatically moved laterally 20 with respect to the knife by the movement of the foot on the inclined surface as the bar is moved toward and from the knife.

13. In a veneer cutting machine, a veneer 25 cutting knife, a coöperating pressure blade, and manually controlled means for varying the relative spacing of the knife and blade to change the thickness of the veneer produced and for automatically maintaining 30 the relative lateral positioning of the blade and knife with respect to and in accordance with the relative spacing of said parts.

14. In a veneer cutting machine, a knife 35 bar provided with a veneer cutting knife and having an abutment provided with a rearwardly and upwardly inclined longitudi-

dinal surface arranged transversely with respect to said knife, a pressure bar arranged above said knife bar and provided with a pressure blade to coöperate with said knife, a support for said pressure bar, the 40 front portion of said bar carrying said blade being movable vertically and provided with a depending rounded foot abutting and slid- 45 able on said inclined surface and upholding said front portion of the pressure bar 45 and determining the vertical position of said blade with respect to said knife, and means for moving said pressure bar to change the spacing between said blade and the knife, said foot elevating said blade as the foot 50 moves rearwardly on said surface and permitting said blade to lower as the foot moves forwardly on said surface.

15. In a veneer cutting machine, a veneer 55 cutting knife, a pressure bar provided with a pressure blade coöperating with said knife, said bar provided with means for shifting the same to vary the spacing between the blade and knife and being movable to vary the lateral position of the blade with respect 60 to the knife, and a longitudinally inclined surface supported independently of said bar and its blade and controlling the lateral position of the blade with respect to the knife, said surface coöperating with said bar to 65 automatically maintain the lateral shifting of the blade at approximately one half the distance of the shifting of the blade for spacing.
